HANG GLIDER

Volmer S. Jensen, 1515 Ard Eevin, Glendale, Calif.
91202, and Irven H. Culver, 225 Redlands, Playa del
Rey, Calif. 90291

Filed May 10, 1973, Ser. No. 359,025

Term of patent 14 years

Int. Cl. D12—07

U.S. Cl. D12—71

FIG. 1.

FIG. 2.

FIG. 3.

FIG. 1 is a top plan view of a hang glider embodying our new design;

FIG. 2 is a front elevational view of the same;

FIG. 3 is a side elevational view of the same, the opposite side being identical.

We claim:

The ornamental design for a hang glider, substantially as shown and described.
